UNITED STATES PATENT OFFICE.

GEORGE J. HALL, OF MALONE, NEW YORK.

GENTLEMAN'S GARTER.

No. 914,268.

Specification of Letters Patent. Patented March 2, 1909.

Application filed August 18, 1908. Serial No. 449,063.

To all whom it may concern:

Be it known that I, GEORGE J. HALL, a citizen of the United States of America, residing at Malone, in the county of Franklin 5 and State of New York, have invented new and useful Improvements in Gentlemen's Garters, of which the following is a specification.

This invention relates to gentlemen's garters, and one of the principal objects of the same is to provide a garter in which a single piece of elastic webbing is used and in which there are no projecting parts.

Another object of the invention is to provide a gentleman's garter which will automatically adjust itself to a proper position for supporting the stocking.

Still another object of the invention is to provide a simple one-piece garter which can be taken off and put on without the use of separable clasps.

These and other objects may be attained by means of the construction illustrated in the accompanying drawing, in which,—

Figure 1 is a front elevation of a garter made in accordance with my invention and applied in position for use. Fig. 2 is a detail perspective view of one of the stocking holders. Fig. 3 is a detail plan view of the double buckle. Fig. 4 is a detail perspective view taken from the inner side of the garter at the point of intersection of the webbing.

Referring to the drawing, the numeral 1 designates a single piece of elastic webbing, 35 to the terminal ends of which are connected the stocking holders 2, said stocking holders each consisting of a metal plate provided with parallel slots 3 and an intermediate cross bar 4. Upon one end of the holder a hook 40 5 is formed, said hook having a series of penetrating prongs 6. These stocking holders are secured to the ends of the webbing 1 by passing the material through the slots 3 and securing the doubled portion by stitches or 45 other suitable fastening.

A double buckle, such as that shown in Fig. 3, is utilized for adjusting the band to the required size to properly encircle the

leg, said buckle comprising the two oppositely disposed buckle members 7 and 8 connected together by an intermediate loop 9, said buckles being pivoted upon the loop. The webbing 1 is passed around the leg immediately above the calf, and the webbing is then adjusted into the buckle member 7 to form a loop 10, the band then being extended back through the buckle member 8 and from thence bound to the stocking holder 2 on the end of the webbing 1 shown at the left of Fig. 1. A short piece of material 11 may be secured to the buckle members upon the inside, as shown in Fig. 4, to prevent contact of the buckle with the leg of the wearer. One end of the webbing 1 is passed through the loop 10, as shown in Figs. 1 and 4, and the two stocking holders are connected to the stocking by engaging the prongs 6 with the ribbed or upper portion of said stocking.

From the foregoing it will be obvious that my stocking holder does not present any projections; is automatically adjustable to the required position, owing to the fact that the webbing is free to move at all points about the leg of the wearer; that the webbing may be quickly adjusted to any sized leg by taking up a portion with the buckle member 7 and forming a loop 10 which represents the amount of take-up or adjustment; that there are no separable clasps to disconnect and connect in order to take off and put on the garter; that the garter may be put on, or taken off, without detachment, from the stocking and without derangement of the adjusting devices, and that the garter can be manufactured at low cost and is very comfortable and efficient for its purpose.

I claim:

1. A garter comprising a single piece of webbing having upon each of its ends a stocking supporter; an integral loop formed in the webbing intermediate its ends through which one end of the garter is passed and an adjusting device connected to the garter at the loop for taking up the webbing to fit.

the leg of the wearer, said loop representing the take up of the webbing in adjusting the garter.

2. A garment supporter comprising a single piece of elastic webbing having a stocking supporter at each end, a double buckle connected to the webbing intermediate its ends to form a loop through which one end of the garter passes, said webbing being

adjustable to the required size, and said loop representing the take-up of the webbing in adjusting the same.

In testimony whereof I affix my signature in presence of two witnesses.

GEORGE J. HALL.
